(57) CLAIM

The ornamental design for plaque remover, as shown and
described.

DESCRIPTION

FIG. 1 is a front elevational view of plaque remover
embodiment my new design;

FIG. 2 is a left side elevational view thereof, the right side
elevational being a mirror image of the side shown;

FIG. 3 is a rear elevational view thereof;

FIG. 4 is a top plan view thereof; and,

FIG. 5 is a perspective view thereof.

The surfaces or portions of the article not shown in the
drawings or described in the specification form no part of the
claimed design.
